UNITED STATES PATENT OFFICE.

LILLIAN E. WASHBURN, OF BLUE STORES, NEW YORK.

WEATHER-SHIELD.

1,169,702.

Specification of Letters Patent. Patented Jan. 25, 1916.

Application filed May 11, 1915. Serial No. 27,372.

To all whom it may concern:

Be it known that I, LILLIAN E. WASHBURN, a citizen of the United States, residing at Blue Stores, in the county of Columbia and State of New York, have invented a new and useful Weather-Shield, of which the following is a specification.

The device forming the subject matter of this application is a canopy and support, adapted to be employed on automobiles for shielding the occupants of such vehicles.

The invention aims to improve the canopy and to provide novel means whereby the canopy may be upheld in operative position.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:—Figure 1 shows the invention in front elevation; Fig. 2 is a bottom plan looking upwardly at the canopy and a part of the supporting structure; Fig. 3 is a perspective of the supporting structure; Fig. 4 is a fragmental vertical section, wherein sundry parts are broken away; Fig. 5 is an elevation of one of the connecting means employed; Fig. 6 is a fragmental transverse section of the canopy.

In carrying out the present invention there is provided a supporting structure or main frame, comprising tubular side posts 1 adapted to be placed upon opposite sides of the seat of an automobile or other vehicle (not shown). The upper ends of the tubular side posts 1 carry sockets 2.

The invention further comprises a U-shaped frame 4 embodying side arms 5, a top bar 6 connecting the side arms, and a tie bar 7 connecting the side arms and located below the top bar 6. The side arms 5 of the U-shaped frame 4 are slidably received in the sockets 2 and in the side posts 1, to permit the U-shaped frame to be raised and lowered, and to the end that the same may be removed when desired. The U-

shaped frame 4 is held in adjusted vertical positions by means of set screws 33 which, being threaded into the sockets 2, engage the side arms 5.

The invention comprises a horizontally disposed, U-shaped support 8, and an upwardly extended, inclined brace 9, the same being provided at its lower end with an eye 10 in which the intermediate portion of the U-shaped support 8 is pivotally received. The rear end of the brace 9 terminates in a socket 11 coöperating with a jaw 12 pivotally mounted as shown at 14, the socket 11 and the jaw 12 being provided with co-operating ears 15 which may be detachably united by means of a bolt and wing nut structure 16 or the like. The socket 11 and the movable jaw 12 constitute means whereby the upper, rear end of the brace 9 may be detachably assembled with the top bar 6 of the U-shaped frame to slide horizontally thereon. The rear ends of the U-shaped support 8 are equipped with connections 34 engaging slidably the tie bar 7. The connections 34 are formed like the parts 11—12 and need not be described in detail. Fixed to and upstanding from the socket 11 is a threaded spindle 17 on which is mounted a spool 18 comprising upper and lower flanges 19, the spool being held in place on the spindle by means of a wing nut 20 or the like.

The invention comprises a foldable, collapsible canopy including resilient ribs 21, the upper, rear ends of the ribs 21 being received by the spool 18 between the flanges 19. Assembled with the ribs 21 is a flexible covering 22 of cloth or other suitable waterproof material. Adjacent their outer, lower ends, certain of the ribs 21 of the canopy are equipped with eyes 23 through which passes a flexible element 24 which may be a light chain. The ends of the flexible element 24 are secured as indicated at 25 to certain of the ribs 21. To the rearmost ribs 21 are attached flexible elements 26 carrying snaps 27 adapted to engage the tie bar 7 of the U-shaped frame 4. The intermediate portion of the flexible element 26 is formed into a rearwardly extended loop 28 carrying a ring 29 pivotally assembled with a snap 30 adapted to be received by the tie bar 7. Projecting laterally from the snap 30 is an eye 31 having an opening 32.

It will be understood that the U-shaped support 8 and the brace 9, together with the canopy may be detached readily from the

parts 6 and 7 when the device is not in use. In order to set up the structure, the lower ends of the side arms 5 are inserted into the upper ends of the side posts 1 and 5 are held in adjusted positions by means of the set screws 33. The clamps or holding devices 34 at the rear ends of the U-shaped support 8 are connected with the tie bar 7, the clamp 11-12 at the rear, upper end of the brace 9 being connected to the top bar 6. In this manner, the support 8 is prevented from sagging downwardly. The spool 18 is slipped over the spindle 17 and the wing nut 20 is applied to the spindle for 10 the purpose of holding the spool in place. The canopy, comprising the ribs 21 is then expanded, the snaps 27 being engaged around the tie bar 7. The looped portion 28 of the flexible element 24 is drawn rearwardly, and the snap 30 is engaged around the tie bar 7. In this manner, the canopy is held down on the support 8, in such a 15 way that it cannot be blown upwardly by the wind.

25 When the occasion for the use of the structure has passed, it may be taken down, in a manner which will be obvious from the foregoing description. The ribs 21 may be swung into alignment, after the manner of a fan, the canopy thus being disposed in a closed form, under which circumstances the flexible element 24 may be employed for binding the canopy into a compact package.

As will be understood readily, the U-shaped support 8 and the brace 9 may be slid toward and away from the respective side arms 5, thereby to position the canopy properly with respect to the occupant of the seat wherewith the said side posts 1 are assembled. A skilled mechanic will understand readily, without a detailed showing that the radius of the U-shaped support 8 may be increased, so that a single support and its canopy may extend entirely across the U-shaped frame 4, from one side arm 5 to the other.

When it is desired to shorten the loop 28, opposed links in the loop 28 are slipped over the ear 31, and through the opening 50 32 may be passed a retaining pin (not shown).

From Fig. 1 of the drawings, it will be entirely obvious that if desired, a second

canopy may be mounted on the parts 6 and 7 so as to project rearwardly.

Having thus described the invention, what is claimed is:—

1. In a weather shield, a supporting frame comprising upper and lower bars; an arcuate support mounted on the lower bar; 60 a brace forming a connection between the arcuate support and the upper bar; a canopy upheld by the support and the brace; means for connecting the ends of the canopy to the lower bar; and means for connecting the 65 intermediate portion of the canopy with the lower bar.

2. In a weather shield, a main frame; an auxiliary frame projecting therefrom; a canopy carried by the auxiliary frame; 70 means for securing the rear portions of the canopy; a flexible element comprising terminal portions and a rearwardly extended intermediate portion; means for securing the rearwardly extended intermediate portion 75 of the flexible element to the main frame; means on the canopy for receiving the terminal portions of the flexible element slidably; and means for securing the extremities of the terminal portions of the 80 flexible elements to the canopy.

3. In a weather shield, a supporting structure comprising a pivot stem; a plurality of superposed ribs mounted pivotally upon the stem and adapted to open and 85 close fanwise; a covering carried by the ribs, the covering and the ribs cooperating to form an approximately semi-conical canopy; and means for securing the rear edges of the canopy detachably to the supporting structure.

4. In a weather shield, a vertically extensible main frame; an auxiliary frame horizontally slideable on the main frame; an expansible, approximately semi-conical 95 canopy detachably and pivotally mounted on the auxiliary frame for opening and closing; and means for holding the canopy in open position.

In testimony that I claim the foregoing 100 as my own, I have hereto affixed my signature in the presence of two witnesses.

LILLIAN E. WASHBURN.
